Des. 196,402
Patented Sept. 24, 1963

196,402

MARINE FLOAT

William R. Brown, Athens, Ga., assignor to Climax Industries, Athens, Ga., a corporation of Georgia

Filed May 15, 1961, Ser. No. 65,168

Term of patent 14 years

(Cl. D71—1)

FIGURE 1 is a top plan view of a marine float, showing my new design;

FIGURE 2 is a side elevational view thereof;

FIGURE 3 is a bottom plan view thereof;

FIGURE 4 is an end elevational view thereof; and

FIGURE 5 is a transverse sectional view on a slightly smaller scale taken along the line 5—5 of FIGURE 3.

I claim:

The ornamental design for a marine float, as shown.
